(57) **CLAIM**

I claim the ornamental design for a wing chair, as shown and described.

DESCRIPTION

FIG. 1 is a perspective view of my wing chair;

FIG. 2 is a front view thereof;

FIG. 3 is a right side view thereof;

FIG. 4 is a left side view thereof;

FIG. 5 is a top view thereof;

FIG. 6 is a back view thereof;

FIG. 7 is a close-up view of a front leg thereof; and,

FIG. 8 is a close-up view of a back leg of my wing chair.

The broken lines shown in the drawings are for illustrative purposes only and form no part of the claimed design.
